TYPEWRITING MACHINE

Henry Joseph Hart, West Hartford, Conn., assignor to Royal Typewriter Company, Inc., New York, N. Y., a corporation of New York

Application July 9, 1937, Serial No. 152,846

2 Claims. (Cl. 197—64)

This invention relates to new and useful improvements in typewriting machines generally, although more particularly to a brake mechanism associated with the tabulator mechanism thereof. 5 One of the objects of the invention is to provide an automatic brake mechanism for retarding the speed of the carriage when the escapement mechanism is released upon depression of a tabular key, whereby the blows of a tabulator stop against the center or tabulator stop finger will be softened and consequently the usual carriage rebound will be prevented and the impact noise will be reduced.

Another object of the invention lies in the provision of such a brake mechanism which will remain ineffective until the carriage has moved a predetermined distance, whereby the speed of the carriage will not be reduced at the time short tabulating jumps are being made at the extreme 20 right hand end of the carriage.

With these and other objects in view which will more fully appear, the nature of the invention will be more clearly understood by following the description, the appended claims, and the several 25 views illustrated in the accompanying drawings.

In the drawings:

Figure 1 is a vertical sectional view of a typewriting machine embodying my invention, the escapement rack bar and the brake being shown 30 in their normal positions.

Figure 2 is an enlarged vertical section showing the escapement rack bar in its elevated position, the brake in its operative position, and a tabulator stop finger in the path of movement of a tabulator stop.

Figure 3 is a front elevation thereof.

Figure 4 is a horizontal section taken on the line 4—4 of Figure 2.

Figure 5 is a detail view showing the carriage 40 rack in its elevated or released position.

Figure 6 is a perspective view showing certain of the rack lifting and brake operating parts in separated relation.

Figure 7 is an enlarged front elevation, partly 45 in section, showing the escapement rack and pinion, and the brake in their normal positions.

Figure 8 is a similar view but showing the rack elevated above the pinion and moved to the left, and the flexible brake coupling at the beginning 50 of the effective braking action.

Figure 9 is an enlarged horizontal section taken on the line 9—9 of Figure 8.

Figure 10 is a vertical section taken on the line 10—10 of Figure 9, and

Figure 11 is a perspective view of the link which

connects the brake mechanism with the tabulator stop finger.

I have shown my invention as applied to a Royal standard typewriting machine such as is shown in the patent to Myers 2,007,611, July 9, 5 1935, although it will be understood that the invention may be applied to other typewriting machines if desired.

This machine includes the usual main frame A which supports a non-shiftable track 2 upon 10 which runs a carriage B having end plates 3 which support a platen 4, the main frame including the usual rear wall 5, and the carriage being normally urged towards the left by the usual spring motor (not shown). 15

The usual escapement mechanism is provided for feeding the carriage at letter space intervals upon depression of a key lever C. This mechanism includes a feed rack bar 6 which is attached to an angle bar or frame 7, and the latter is provided with rearwardly extending arms 8, 8 which are pivoted to the end plates 3, 3 of the carriage as at 9, 9. The carriage also includes the stop bar 10 on which the usual margin stops are mounted for engagement with the usual center 20 stop lever. Springs 11 are connected to the arms 8 and the stop bar 10 and function to normally retain the rack bar 6 in engagement with an escapement or feed pinion 12 which is journaled on a shaft 13 mounted on the bracket 17. An 25 escapement wheel 14 which is mounted to rotate with the pinion 12 cooperates with the usual escapement dog (not shown). A rack bar lift lever or operating member 15 is pivoted as at 16 on the bracket 17 which is mounted on the car- 30 riage track 2 and in which the shaft 13 is journaled. The lift lever 15 is disposed under the rack bar 16 and is provided with a downwardly 35 extending arm 18. The lift lever 15 is raised in the usual manner upon depression of the tabular key lever E to thereby release the escapement 40 and effect a jump movement of the carriage.

Supported by the end plates 3, 3 of the carriage is a tabulator stop frame D which supports a plurality of tabular stops 19 arranged at letter 45 space intervals. These stops are individually swingable forwardly and rearwardly from an operative position to an inoperative position, or vice versa. A bracket 20 is fixed centrally to the rear wall 5 of the main frame A, and mounted to swing 50 about a horizontal pivot 21 on said bracket is a tabulator stop finger or center stop 22. The upper end of the finger 22 projects upwardly in rear of the stop frame D, and is movable forwardly into the path of the tabular stops 19 when the 55

latter are in their rearmost or operative positions. A link 23 is pivoted at its forward end as at 24 to the rack lift lever 15, and at its rear end as at 25 to a rock arm 25a which is movable with the stop finger 22. A horizontal bracket 26 is attached to the front face of the rear wall 5 of the main frame, and fulcrumed on said bracket to swing about a vertical axis 27 is a power transmitting lever 28 having a long arm 29 and a short arm 30, the long arm having a projection 29a which is disposed in rear of the depending arm 18 of the rack lift lever 15 and forms a loose connection therewith whereby the escapement mechanism will be released whenever a tabular key lever 15 E is depressed. A power transmitting lever 31 is also fulcrumed on the bracket 26 to swing about a vertical axis 32, and includes a long arm 33 and a short arm 34, the latter being disposed in front of the short arm 30 of the lever 28 and in overlapping relation therewith whereby upon forward movement of the long arm 33 the long arm 29 of the lever 28 will be moved forwardly to swing the arm 18 of the rack lift lever and thereby release the rack bar 6 from the pinion 12 and simultaneously swing the tabulator stop finger 22 into the path of the tabular stops 19. The tabular key lever E is located in the key board and preferably on the right hand side thereof. This lever E is fulcrumed on the main frame A as at 35 and is yieldably held against depression by a spring 36, the spring normally retaining the lever against a stop 37 mounted on the main frame. The lever E is provided with an upstanding arm 38 which is pivotally connected to the front end of a link 39, the rear end of the link having pivotal connection with the long arm 33 of the transmitting lever 31. Thus upon depression of the tabular key lever E the rack 6 will be separated from the pinion 12 to thereby free the carriage B from the escapement mechanism and simultaneously move the stop finger 22 forwardly into the path of the oncoming tabular stop 19. Upon release of the key E the rack 6 will return to its normal position in engagement with the escapement pinion 12 and the carriage will be retained against further movement by the holding dog of the usual escapement.

An automatic brake mechanism is provided for retarding the speed travel of the carriage when the carriage feed rack 6 is released from the pinion 12 upon depression of the tabular key lever E, thereby softening the blow or impact of the tabular stops 19 against the tabulator stop finger or center stop 22 and also preventing any rebound of the carriage.

To this end, the rack lift lever 15 is provided with a laterally projecting ear or arm 40, and fixed thereto is a forwardly extending bearing shaft 41 and journaled on this shaft are a restrained member or friction brake drum 42 and a pinion member 43 which are coupled together by a flexible coupling comprising a coil spring 44 having its ends respectively anchored to said drum and pinion. The pinion is normally disposed below and out of contact with the rack 6 but is adapted to be elevated into engagement therewith when the rack is elevated by the rack lift lever 15. Fixed to the inner face of the brake drum 42 are two stop pins 45, 46 which are spaced apart less than 180°, preferably 90°. A stop pin 47 which is fixed to the inner face of the pinion 43, normally engages the pin 45 and is adapted to rotate with the pinion more than 180°, preferably 270°, or from the stop pin 45 to the stop pin 46 as shown 75 in Figs. 7 and 8. A brake lever 48 is fulcrumed

intermediate its ends as at 48a on the arm 40 of the rack lift lever 15 so as to rock about an axis transverse to the axis of the pivot 16. The upper arm 49 of the brake lever terminates in a brake arm or shoe 50 which overhangs the drum 42 and the lower arm 51 of said lever is provided with a longitudinal series of seats 52 for adjustably receiving one end of a tension spring 53, the other end of said spring being connected to the rack lift lever 15. The pivot 48a of the brake lever is eccentric to the axis of the brake drum 42, and consequently the brake arm or shoe 50 will be held in frictional engagement with the drum periphery, the amount of friction being regulated by adjusting the connection between the spring 53 and the seats 52 of the brake lever arm 51.

In operation, predetermined tabular stops 19 are swung rearwardly into positions to successively engage the tabulator stop finger or center stop 22 upon successive depressions of the tabular key lever E. When the key lever E is depressed, the rack lift lever 15 will be rocked to (1) lift the rack 6 from engagement with the feed pinion 12, and (2) simultaneously connect the brake pinion 43 with said rack. The carriage B is then moved to the left by the usual spring motor, and the brake pinion 43 is thereby freely rotated until the stop pin 47 of the pinion engages the stop pin 46 of the drum, during which time the spring 44 is tensioned. Consequently, while the pinion 43 is rotating over 180°, there will not be any braking action imparted to the carriage by the drum and the braking lever, but immediately upon the stop pin 47 of the pinion 43 contacting the stop pin 46 of the drum, the latter will rotate in unison with the pinion and the carriage movement will be retarded by the brake. Upon release of the tabular key lever E, the escapement mechanism will become effective, the pinion 43 will be lowered out of contact with the rack bar 6, and the spring 44 will rotate the brake pinion 43 until the stop pin 47 engages the stop pin 45 of the brake drum 42. The pins 45 and 46 on the brake drum 42 and the pin 47 on the pinion 43 cooperate to function as a lost motion connection for positively coupling the rack-driven pinion member 43 with the frictionally restrained brake drum member 42 only after the carriage has moved an appreciable distance on the frame.

The travel of the carriage during successive jumps, is determined by the spacing of the tabular stops, and during each jump the braking action on the carriage will not become effective until the carriage has moved a distance determined by the travel of the stop pin 47 of the pinion 43 from the stop pin 45 to the stop pin 46 of the drum, during which time the pinion 43 is in mesh with the carriage rack 6 and has rotated a predetermined distance. Thus the braking action on the carriage is deferred by said flexible coupling, until the pinion 43 has completed a partial rotation, thereby permitting the carriage to start and gain a slight headway before the brake is applied. This deferred or delayed braking action on the carriage is of particular value when making short tabulating jumps at the extreme right hand end of the carriage because it permits the carriage to make the short jump or jumps without affecting the speed thereof.

It is of course to be understood that the details of structure and arrangement of parts may be variously changed and modified without departing from the spirit and scope of my invention.

I claim:

1. In a typewriting machine, the combination
with a travelling carriage having a rack, of a
pivotally mounted operating lever; a shaft car-
ried by said operating lever; a pinion journaled
on said shaft engageable at will with the rack;
5 a brake drum journaled on said shaft; a driving
connection between said pinion and drum; a
brake lever fulcrumed on said operating lever
and being movable therewith and with respect there-
10 to and having a shoe adapted frictionally to en-
gage the drum; and a spring interposed between
and connected respectively to said operating lever
and said brake lever for urging the latter about
15 its fulcrum on the operating lever to press the
brake shoe into engagement with said drum.

2. In a typewriting machine, the combination
with a travelling carriage having a rack, of a
pivotally mounted operating lever; a shaft car-

ried by said operating lever; a pinion journaled
on said shaft engageable at will with the rack;
a brake drum journaled on said shaft; a driving
connection between said pinion and drum; a
brake lever fulcrumed on said operating lever
and being movable therewith and with respect thereto
5 and having a shoe adapted frictionally to engage
the drum; and a spring interposed between
and connected respectively to said operating lever
and said brake lever for urging the latter about
10 its fulcrum on the operating lever to press the
brake shoe into engagement with said drum.
15

HENRY JOSEPH HART.
